MACHINE FOR OPERATING UPON SOLES

Ernest W. Stacey, Beverly, Mass., assignor to
 United Shoe Machinery Corporation, Paterson,
 N. J., a corporation of New Jersey

Application May 26, 1934, Serial No. 727,765
 In Great Britain March 27, 1934

42 Claims. (Cl. 12—17)

This invention relates to machines for operating upon soles for shoes and is herein illustrated as embodied in a machine for automatically rounding an outsole, reducing and roughing its marginal portion to prepare it for attachment by means of cement to the bottom of a shoe and performing a final smoothing and finishing operation upon the edge of the sole.

An outsole which is to be attached to a shoe by means of cement is cut approximately to final edge contour and the marginal portion at the flesh or attaching side of the sole is roughened to prepare it for the reception of the cement so that a satisfactory bond will be insured between the cement and the substance of the sole. In most instances, the marginal portion of the sole is beveled at a substantial angle along the opposite sides of its shank portion and usually it is also beveled, although at a somewhat less angle, around its forepart. It is a common practice also to smooth and finish the sole edge, at least in the forepart of the sole, by a final edge trimming operation performed before the sole is attached to the shoe.

One object of the present invention is to provide a machine capable of performing some or all of the above-mentioned operations which will operate rapidly and in such a manner as to insure superiority in the character of the work performed as well as substantial uniformity of results upon the different soles operated upon.

With the above object in view, one feature of the present invention consists in the provision, in a machine for operating upon soles, of a reducing and roughing tool and means for relatively moving the tool and a sole to cause the tool to perform a combined roughing and edge reducing operation upon the sole. Other features of invention will be recognized as residing in novel mechanisms for performing rounding, reducing, roughing and edge trimming or finishing operations, or various combinations of such operations, upon a sole.

In the embodiment of the invention herein illustrated, a sole to be operated upon is clamped against the lower side of a pattern in such a manner as to leave the marginal portion at the attaching side of the sole unobstructed so that it may be acted upon by the operating instrumentalities of the machine. As illustrated, these instrumentalities comprise a tool in the nature of a milling cutter for performing an initial rounding operation upon the sole, a plurality of cutters for beveling at a relatively steep angle and simultaneously roughing the marginal portion at the shank of the sole, a plurality of cutters for beveling at a

substantially less angle and simultaneously roughing the marginal portion at the forepart of the sole, and a trimming cutter for performing a final edge trimming or finishing operation around the forepart of the sole. These cutters are mounted upon two cutter heads which are arranged to rotate about parallel axes perpendicular to the plane of the sole, the rounding cutter and the beveling and roughing cutters for the shank portion of the sole being mounted upon one of the cutter heads while the beveling and roughing cutters for the forepart of the sole and the edge trimming cutter are mounted upon the other cutter head. The cutter heads are mounted in a carrier which carries also two guide rolls for cooperating with the pattern to control the positions of the cutters relatively to the sole, the carrier being pivotally supported on a swinging arm which is spring-pressed toward the pattern so that both rolls will be maintained in cooperative relation to the pattern. The pattern is carried by a jack to which both turning and straight line movements are imparted at each cycle of operations of the machine to cause the sole margin to move with a substantially constant velocity past the cutters.

In order that the beveling and roughing cutters which act to produce a relatively steep bevel in the shank portion of the sole shall not operate also to produce a similarly steep bevel at the heel and around the forepart of the sole, the cutter head which carries these cutters is mounted for axial movement and provision is made, as herein illustrated, for maintaining the cutter head in a normal elevated position while the shank portion of the sole is being moved past it and for retracting or lowering the cutter head and maintaining it in a retracted position wherein its beveling and roughing cutters will be removed from operative engagement with the work during such times as the heel and forepart portions of the sole margin are being moved past these cutters. As illustrated, also, the cutting edges of the beveling and roughing cutters on both cutter heads are toothed to cause them to roughen the beveled surfaces which they form upon the soles and the fact that the toothed cutting edges of these cutters are inclined to the axes of rotation of the cutter heads, so that the cutters will bevel the sole margin as well as roughen it, causes the toothed edges to cut grooves or furrows in the sole margin along lines which are envelopes of the arcs described by the cutter teeth as the latter rotate and which consequently extend along lines parallel to the edge of the sole. The illustrated edge trimming cutter is provided with cutting teeth

55

which are shaped to provide a beaded finish to the sole edge and inasmuch as the finish of that character is usually desirable only about the fore part of the sole where the sole edge is of substantial thickness, provision is made in the illustrated machine for moving the edge trimming cutter under the control of the pattern in a direction away from the sole edge an amount just sufficient to retract the edge trimming cutter from 10 work-engaging position while the shank portions of the sole are being moved past that cutter.

It will be observed from the foregoing that the illustrated machine is provided with novel mechanism whereby, at a single traverse of the sole 15 margin past the beveling and roughing cutters, the latter are caused to cut a relatively steep bevel in the shank portion of a sole and a relatively shallow bevel at the heel and forepart portions of the sole; a novel arrangement of means 20 for roughening the sole margin by cutting furrows therein which extend in directions parallel to the sole edge; and novel mechanism for edge finishing a portion only of the sole edge constitute further features of the invention. These 25 novel mechanisms and arrangements of parts constitute further features of the present invention.

The invention also consists in other features of construction and combinations and arrangements of parts hereinafter described and pointed out in the claims, the advantages of which will be apparent to those skilled in the art.

The invention will be described with reference to the accompanying drawings, in which

35 Fig. 1 is a view in side elevation of the upper portion of a machine in which the present invention is embodied;

Fig. 2 is a view in vertical section of a portion of the head of the machine;

Fig. 20 is a cross-section taken along the line XX—XX of Fig. 18;

Fig. 21 is a perspective view of one of the cutter heads showing the beveling and roughing cutters which operate upon the shank portion of the sole, the rounding cutter having been removed; 20

Fig. 22 is a rear elevational view of the lower 25 part of the machine showing a portion of the driving mechanism;

Fig. 23 is a horizontal section showing the pattern and associated work-guiding cam and the cutter head carrier, and illustrating particularly 30 the relative positions of those parts when the jack is in its initial position of rest;

Fig. 24 is a fragmentary view of the parts shown in Fig. 23 but showing their relative positions shortly after the start of a cycle of operations of the machine; 35

Fig. 25 is a view similar to Fig. 24 but showing the parts as they appear at a later stage in the cycle of operations;

Fig. 26 is like a portion of Fig. 25 except that 40 the pattern and the guide rolls have been removed the better to illustrate the operation of the cutters upon the work; and

Fig. 27 is like a portion of Fig. 25 but shows the parts as they appear at a still later stage in the 45 cycle.

Referring first to Figs. 1 and 3 of the drawings, which when placed one above the other show the whole machine in side elevation, the machine comprises a base or frame 50 in which most of 50 the driving mechanism is contained and a head 52 that is bolted to the base. Mounted in the head 52 is a jack 54 having means for removably supporting thereon a sole pattern of a selected size and style, such, for example, as the pattern 55 P, and having also means including two clamp members 58 and 60 for clamping the work, such as the block outsole S, to the pattern. The pattern and the block sole are supported with their longitudinal axes inclined at approximately 45° to 60 the horizontal since it has been found that this position permits the operator to present the work to the machine and to remove it therefrom with the least effort. The jack 54, together with a pattern supported thereon and an outsole clamped 65 to the pattern, are adapted to be moved bodily with respect to the operating instrumentalities of the machine to cause the latter to operate progressively along the marginal portions of the sole. The operating instrumentalities comprise a plurality of cutters carried by two rotary cutter heads 62 and 64 (see Figs. 8, 10 and 12) which are mounted upon an oscillatory carrier 66 and the carrier 66 is mounted at the free extremity of a movable carrier supporting arm 68, the oppo- 70

75

site end of which is fast upon an upright shaft 10 (best shown in Fig. 8) that is mounted to turn in a bearing 12 in the frame 50 so that the arm 68 may swing to permit the cutters to be moved toward and from operative relation to the work. The cutters comprise a rounding or milling cutter 16 which is carried by the cutter head 62 and is adapted to perform an initial rounding or rough trimming operation upon the work, a plurality of cutters 78 which are also mounted upon the cutter head 62 and which operate upon the shank portion of the sole to perform a combined reducing or beveling and roughing operation upon the sole margin, a plurality of cutters 80, mounted upon the cutter head 64, for operating around the forepart of the sole to perform a combined reducing or beveling and roughing operation upon the sole margin, and a cutter 82 carried by the cutter head 64 for performing a final edge trimming and finishing operation around the forepart of the sole. The cutter heads 62 and 64 are rotated continuously at high speed while the machine is in use. The cutter head 62 is mounted for axial movement enabling it to be raised and lowered relatively to the carrier 66 to move the cutters 78 toward and from positions to operate upon the work while the work is being fed past the cutters, the raising and lowering of the cutter head, however, having no effect upon the action of the rounding cutter 16 which remains operative during the entire traversing movement of the sole. The cutter head carrier 66 is provided also with two guide rolls 84 and 86 which are located above the cutters in coaxial relation with the cutter heads 62 and 64, respectively. The arm 68 which supports the cutter head carrier 66 is spring-pressed forwardly to hold the guide rolls 84 and 86 in yielding cooperative engagement with the pattern P or with a cam 88 carried by the jack, thereby to determine the path of relative traversing movement of the cutters and the work. The cutter head carrier 66 is pivotally mounted in its supporting arm 68 so that it may tilt relatively to the arm 45 during the relative traversing movement of the cutters and the work as required to maintain both guide rolls in engagement with the pattern. As herein illustrated, the guide roll 86 is formed with a lower peripheral tongue portion 90 of enlarged diameter for cooperating with the pattern to tilt the carrier 66 in a manner to retract the edge trimming or finishing tool 82 from the sole while the shank portion of the sole is being operated upon an amount just sufficient to render the edge trimming tool 82 inoperative upon the shank portion of the sole while not appreciably affecting the action of the beveling and roughing cutters 80. This insures that the edge trimming cutter 82 shall operate only around the forepart 60 and at the heel portion of the sole. A third roll 92 is mounted upon the cutter head carrier 66, beneath the roll 84, for cooperation with the pattern to effect the raising and lowering of the cutter head 64 for the purpose of moving the shank beveling and roughing cutters 78 to and from operative work-engaging positions. The clamp members 58 and 60 are carried by a clamp frame 96 which is mounted upon the jack and is normally held by spring pressure in a work 70 clamping position. A foot treadle 98 is connected with the clamp frame for use in lowering the latter to retract the clamp members from the sole so that a sole which has been operated upon may be removed and a new sole inserted in the 75 machine. A second foot treadle 100 is provided

for starting the cycle of operations of the machine. Springs 102 connected with the treadles 98 and 100 tend to hold them in elevated positions. During each cycle of operations, the jack is moved to cause the marginal portion of the sole to be traversed by the cutters from a point at one side of the heel of the sole forwardly along the shank and forepart, around the toe and then rearwardly along the forepart and shank at the opposite side of the sole to a point at the heel part opposite the point where the operations began. The sole has then been rounded, its marginal portion beveled and roughened, the angle of bevel in the shank portion being greater than the angle of bevel in the forepart, and the sole 15 edge smoothed and finished around the forepart. The operator then depresses the clamp treadle 98 and removes the sole from the machine. The pattern is removable and it is to be understood that a different pattern is required for each different size of sole to be operated upon.

The jack 54 comprises a rigid box-like upper structure or carriage 106 which is open at the top and bottom and has elongated parallel side members 108 (see Figs. 13 to 16) which are connected at their opposite ends by means of blocks 110 and 112, the latter being rigidly secured to the side members 108 by means of screws 114. Formed in the inner faces of the side members 108 above the blocks 110 and 112 are two longitudinal grooves 116 (Fig. 16) into which extend two flanges 118 formed on the opposite sides of a rectangular plate 120 which is integral with a sleeve 122 rotatably mounted on a post 124 that is rigid with the head 52 and extends obliquely 30 downward, the sleeve 122 being held from slipping off the bottom of the post 124 by a round, rabbeted plate 126 (Figs. 2 and 13) fastened to the bottom of the post by means of screws 128. As shown in Fig. 2, the post 124 is received in a 40 bore in the head 52 and is held rigidly in place by means of a draw bolt 130. With this construction, the jack carriage 106 is enabled to slide longitudinally at times on the plate 120 while the plate 120 and the jack carriage 106 are adapted 45 to turn as a unit at times about the axis of the post 124.

The means for effecting the above-described sliding and turning movements of the jack carriage 106 comprise a driven pinion 132 which 50 meshes with the teeth of an endless rack 134 formed upon the inside of the jack carriage 106. The endless rack 134 comprises two straight rack sections 136 and two curved rack sections 138 (Figs. 14 and 15). The straight rack sections 55 136 are formed upon the inner faces of the side members 108 of the jack carriage and extend lengthwise of the latter. The blocks 110 and 112 which connect the opposite ends of the side members 108 have inner walls which are semi-circular in cross-section and the curved rack sections 138 are formed on these semicircular inner walls of the blocks 110 and 112. For the purpose of guiding the jack carriage 106 in its sliding and turning movements, two guide members 60 140 and 142 are located in spaced relation above the blocks 110 and 112 and are rigidly secured to the upper edges of the side members 108 and one or both of these guide members are adapted to be held at times in contact with a straight stationary guide rail 144 (Figs. 14 and 15) which is secured by means of screws 146 to the head 52. The effective portion of each of the guide members 140 and 142 is U-shaped, the outlines of the curved ends of these portions inside and outside 75

being semicircles and the inner walls of the guide members registering with the semicircular rack sections.

The pinion 132 which drives the jack is fast upon the lower end of a hollow shaft 148 which is mounted to rotate in an eccentric bore in the post 124 and which has fast upon its upper end a bevel gear 150 meshing with a bevel pinion 152 on the upper end of an upright shaft 154 rotation of which is initiated by depression of the starting treadle 100.

From the foregoing it will be seen that the jack is suspended from the head of the machine in such a manner that it is always free, when permitted to do so, either to slide in the direction of its length or to rotate about the center of one or the other of the curved outer faces of the two guide members 140 and 142 and that the jack is driven by means including the pinion 132 which engages the endless rack 134 and holds the guide member 140 or the guide member 142 or both of these guide members against the guide rail 144. In its position of rest (shown in Figs. 1 and 14), the jack carriage 106 is disposed with its longitudinal axis perpendicular to the guide rail 144 and the guide member 142 is in contact with the guide rail. When a cycle of operations of the machine is started the jack will first swing 90° counterclockwise (viewed from above) about the center of curvature of the curved outer face of the guide member 142 until the guide member 140 is brought into contact with the guide rail 144 so that no further rotation can take place. The jack will then slide along the guide rail 144 toward the left until it is stopped by engagement of the inner face of the guide member 140 with the sleeve 122, whereupon no further straight line slide movement can take place. The jack will then rotate counterclockwise 180° until the guide member 142 strikes the guide rail 144. The jack will then slide along the guide rail toward the left until stopped by engagement of the inner face of the guide member 142 with the sleeve 122. The jack will then rotate 90° to its starting position whereupon the machine will be automatically stopped as the result of mechanism brought into operation by means of a cam 156 on the guide member 142. It will be noted that the guide rail 144 has bent ends, one of which is shown, having slots 157 (Fig. 15) through which screws 146 extend, the slots permitting the ends of the guide rail to slide upon the screws. The ends of the guide rail are supported by coiled springs 158 which are interposed between the rail and the head of the machine so as to cushion the blows of the jack when it has been rotated through 180° and one or the other of the guide members 140 or 142 strikes the guide rail.

The jack carriage 106 has rigidly secured to it two depending brackets 162 and 164 for supporting the pattern P each bracket having at its lower end a dowel pin 166, the dowel pins being adapted to fit tightly in holes 168 in the pattern. As shown, the bracket 164 comprises a lower portion which carries the dowel pin 166 and which is secured to the upper portion of the bracket by means of a bolt and a nut 165. The pattern P may advantageously be made of wood and except for certain novel features to be described it is similar to the patterns commonly employed in machines of the well-known Planet Sole Rounder type, the edge of the pattern being shaped to correspond to the outline which it is desired to impart to the sole. The holes 168 extend entirely through the pattern thus enabling the pattern to

be reversed or turned bottom upward so that the same pattern can be used for both right and left soles. As best shown in Fig. 17, each side of the pattern is faced with a thin layer 170 of finely divided particles of abrasive material to assist in preventing the work from slipping relatively to the pattern after it has been clamped to the latter. That portion of the edge of the pattern which lies adjacent to one side of the pattern cooperates with the guide roll 84 and with the upper and relatively small portion of the guide roll 86 in controlling the action of the cutters when a right sole is being operated upon and that portion of the pattern edge which lies adjacent to the opposite side of the pattern cooperates with the rolls 84 and 86 in controlling the action of the cutters while operating upon a left sole, the pattern being positioned in either case so that the portion of its edge which is to cooperate with the guide rolls as above described shall be uppermost. The pattern is securely held in place upon the brackets 162 and 164 while the machine is in operation by the upward pressure exerted by the clamps 58 and 60 against the sole. The pattern may be readily removed from the dowel pins 166 when the clamp frame is lowered to enable the pattern to be reversed or replaced by a pattern of a different size or style for use in operating upon a sole of a corresponding size or style.

The guide roll 92 and the relatively large lower portion 90 of the guide roll 86 are adapted to engage the edge of the pattern along the shank portion of the latter and along an area substantially midway between the opposite sides of the pattern. In order to prevent the guide roll 92 and the portion 90 of the guide roll 86 from cooperatively engaging the edge of the pattern around the forepart and at the heel end of the latter, the forepart of the pattern is provided with a groove 172 (Fig. 17) which extends around the edge of its forepart and with grooves 174 in the pattern edge at the heel end of the pattern, these grooves being located midway between opposite sides of the pattern so that when the pattern has been properly placed in the machine the grooves will receive the guide roll 92 and the portion 90 of the guide roll 86 as the pattern is moved past the guide roll.

The clamp frame 96 which carries the clamp members 58 and 60 by means of which the sole is clamped against the pattern is made in the general form of an ordinary C-clamp having straight horizontally disposed upper and lower portions 176 and 178, respectively, and an upright intermediate or connecting portion 180. The clamp frame 96 is carried by the jack carriage 106 and is adapted to be raised and lowered relatively to the pattern for the purpose of clamping and releasing the work. To this end the clamp frame 96 is mounted and operated as follows.

The clamp frame 96 is carried by the long arms of two bell crank levers 184 and 186 which are fulcrumed in the upper portions of the brackets 162 and 164 which support the pattern. The long arms of the bell crank levers 184 and 186 are made in the form of yokes to straddle the upper portion 176 of the clamp frame 96 and two trunnions, one of which is shown at 192, project from opposite sides of the clamp frame portion 176 near the upright portion 180 and are mounted to turn in the free ends of the yoke arms of the bell crank lever 184, while two similar trunnions, one of which is shown at 194, project

from opposite sides of the upper clamp frame portion 176 near the free extremity of the latter and are mounted to turn in the free ends of the yoke arms of the bell crank lever 186. The downwardly extending short arm portions 196 of the bell crank lever 184 are connected by means of links 198 with the opposite sides of the downwardly extending short arm 200 of the bell crank lever 186, thereby connecting the levers 184 and 186 for rocking movements in unison for the purpose of raising and lowering the clamp frame 96. Springs 202, each connected at one end with the short arm portions 196 of the lever 184 and at its opposite end with a portion of the bracket 164, and springs 204, each connected at one end with the short arm 200 of the lever 186 and at its opposite end with a fixed post 206 mounted on the jack carriage 106, tend to rock the levers 184 and 186 in directions to hold the clamp frame 96 in its upper or work-clamping position. The clamp frame is adapted to be lowered into a position to release the work by means of a push rod 210 which extends through the hollow shaft 148 which supports the driving pinion 134. The lower end of the push rod 210 bears against the upper edge of the upper clamp frame portion 176 and the upper end of the push rod is pivoted at 212 (Figs. 1 and 2) to a lever 214 which is fulcrumed upon a stud 216 carried by the head 52 and which is acted upon by means of a spring-pressed plunger 218, the force of which tends to lift the lever. The lever 214 is adapted to be swung downwardly for the purpose of lowering the clamp frame 96 by means comprising a rod 220 which connects the free extremity of the lever 214 with the long arm of a bell crank lever 222 which is fulcrumed upon a stud 224 carried by the frame 50. The short end of the bell crank lever 222 is connected by means of a rod 226 with an arm 228 fast on a shaft 230 to which is fixedly secured the foot treadle 98. The above-described construction of the operating connections between the treadle 98 and the push rod 210 is such that depression of the treadle 98 will result in a lowering of the clamp frame against the force of the springs 202 and 204, and release of the treadle 98 will permit those springs to raise the clamp frame into work-clamping position.

The clamps 58 and 60 which are carried by the lower portion 178 of the clamp frame 96 are each provided with work-engaging surfaces which are each shaped in outline as best shown in Fig. 9 to engage the sole only in areas spaced inwardly from the marginal portions which are to be operated upon by the roughing cutters 78 and 80, and which are finely serrated, as indicated at 232, to facilitate holding engagement with the work. The clamp 58 is secured directly to the lower clamp frame portion 178 by means of bolts 234 and 236 (see also Fig. 9a), these bolts extending through a slot 237 which extends lengthwise of the lower portion 178 of the clamp frame and thus enables the clamp to be adjusted for soles of different lengths. The bolt 236 also extends through an arcuate slot 238 in the base of the clamp 58, this slot being so arranged that, by loosening the bolt 236, the clamp 58 may be rotatably adjusted to a limited extent about the bolt 234 to adjust the clamp between two positions, in one of which the clamp is adapted properly to engage a right sole and in the other of which it is adapted properly to engage a left sole. The clamp 60 is formed at the upper end of a cylindrical stem 240 which is slidably received within a tubular support 242,

the lower portion of which is secured by means of bolts 244 and 245 to the lower portion 178 of the clamp frame 96. The bolt 244 extends through an arcuate slot 246 in the base of the tubular support 242 arranged to permit a limited amount of rotational adjustment of the clamp 60 about the bolt 245 to adapt the clamp to accommodate both left and right soles. The bolts 244 and 245 extend also through a slot 247 in the portion 178 of the clamp frame to permit adjustment of the clamp 60 to accommodate soles of different lengths. A spring 248 confined within the tubular support 242 beneath the clamp stem 240 urges the clamp 60 upwardly, the upward movement of the clamp 60 being limited by engagement of a stop screw 249 with the upper end of a slot 250 which is formed inside of the support 242 and through which the stop screw 249 projects. The screw 249 by engagement with the sides of the slot 250 serves to prevent the clamp 60 from turning relatively to its support 242.

In addition to carrying the pattern and the clamp frame, the jack carriage 106 carries also the cam plate 88 already referred to (see Figs. 8, 9 and 23 to 25), the cam plate 88 being fixedly secured to the pattern supporting bracket 162 and having an edge face 256 for cooperative engagement with the guide rolls 84 and 86 in determining the positions of the cutters at the beginning and at the ending of each cycle of operations when the jack is leaving or approaching its position of rest in which it is shown in Figs. 1, 14 and 23. For this purpose, the cam plate 88 is located in the plane of the pattern at the heel end of the latter so that it constitutes in effect a rearward extension of the pattern. As shown, the cam plate 88 is apertured to receive the upright portion 180 of the clamp frame 96, thereby permitting the clamp frame to move freely through the aperture as the clamps 58 and 60 are moved to and from work-engaging positions. The cam plate 88 operates to effect the retraction of the various cutters and the guide rolls from cooperative relation to the work and the pattern respectively during the latter part of each cycle of operations of the machine to insure that the upright portion 180 of the clamp frame shall not be moved into engagement with the cutters and to facilitate the removal from the pattern of the sole which has just been operated upon and the placing of a new sole in proper position upon the pattern.

In order that the guide rolls may be yieldingly held in engagement with the pattern or with the cam plate 88 during the operation of the machine, and in order that the cutters may be retracted from the work at the completion of each cycle of operations, the arm 68 which carries the cutter head carrier 66 is mounted for swinging movement relatively to the jack, the right-hand end of the arm 68 being fast upon the shaft 70 which is mounted to turn in the bearing 74 in the frame of the machine, as has been already explained. At its free extremity, the arm 68 is connected by means of a cable 260 (Figs. 8 and 9) with the upper end of a strong spring 262 (Fig. 3), the lower end of which is secured to the frame 50, the cable passing over an idler pulley 264 and the force of the spring tending to swing the arm 68 forwardly to hold the guide rolls 84 and 86 in engagement with the pattern or the cam plate 88 and to maintain the cutters in operative relation to the work. In order that the arm 68 may be swung rearwardly so as to re-

tract the cutters from the work to facilitate removal or adjustment of the cutters, a hand lever 266 is pivoted at 268 on the frame of the machine, the lever being normally retracted from 5 operative engagement with the arm 68 and being so arranged that it may be moved manually to engage the arm 68 and retract the latter against the force of the spring, the lever being movable into such a position that it will maintain the 10 arm 68 in its rearwardly displaced position until the lever is manually swung in the opposite direction for the purpose of releasing the arm. As shown, the arm 68 is a hollow box-like structure, the forward portion of which is open toward the 15 front of the machine to receive the rear portion of the cutter head carrier 66 and to receive also the dust produced by the various cutting operations, the interior of the arm being connected by means of a flexible conduit 270 with a blower 20 272 (Fig. 3) which is operated to carry away the dust. A flexible gate 274 (Fig. 9) carried by the arm 68 yieldingly engages the rear edge of the pattern for the purpose of sealing the dust-receiving opening leading to the conduit 270.

25 The cutter head carrier 66 (Figs. 10, 11 and 12) comprises a lower portion 280 which carries the cutter heads 62 and 64, and an upper portion 282 which is connected with the lower portion by a web 284 and which carries the guide 30 rolls 84, 86 and 92. The cutter head carrier 66 is pivotally mounted upon the arm 68 to enable the carrier to turn freely about an axis which is perpendicular to the sides of the pattern and is located midway between the axes of the guide 35 rolls 84 and 86 so that both the roll 84 and the roll 86 may be maintained in engagement with the pattern as the pattern is moved past the rolls. For this purpose, a block 286 (Fig. 10), which is secured by means of a bolt 290 to the lower portion 30 280 of the cutter head carrier 66, is provided with a depending trunnion 292 which is adapted to turn in a bearing formed in a plate 294 which is bolted to downward extensions of the walls of the hollow arm 68 and the upper portion 282 of the carrier 66 is socketed to receive a fixed stud 296 (Fig. 10) which is coaxial with the trunnion 292 and which is carried by a plate 298 that is bolted to the upper wall of the hollow arm 68. The common axis of the trunnion 292 and the stud 296 is located in line with and midway between the axes of the guide rolls 84 and 86.

The guide rolls 84 and 86 are mounted to turn upon studs 300 (Figs. 9, 10 and 11) which depend 55 from blocks 302 carried by arms 304 which project forwardly from the upper portion 282 of the cutter head carrier and are rigidly secured to the latter by means of bolts 306. The guide rolls 84 and 86 are held on the studs 300 by the heads 60 of screws 308 carried by the studs, the head of the screw associated with the guide roll 84 being countersunk in the lower side of that roll to avoid interference with the roll 92 located just beneath the roll 84 and mounted independently of the 65 latter, as will be hereinafter explained. In order that the guide rolls 84 and 86 may be adjusted relatively to the cutter head carrier 66 to vary the operative relations of the cutter heads to the work, the blocks 302 are mounted in slots 310 in 70 the outer ends of the arms 304 and screws 312 are provided for adjusting the blocks in the slots 310. The adjusting screws 312 extend through and are adapted to turn freely within bores 314 formed in the blocks 302 and have threaded engagement with the arms 304. The blocks 302 are

confined between the heads of the adjusting screws 312 which engage the front ends of the blocks and collars 316 (Fig. 11) on the screws which engage the rear sides of the blocks so that by turning the screws 308 the guide rolls 84 and 5 86 may be adjusted forwardly or rearwardly with respect to the carrier 66. After being thus adjusted the blocks 302 are rigidly secured to the arms 304 by means of nuts 318 on threaded studs 320 which extend upwardly from the blocks, suitable washers 322 being provided between the nuts 10 and the arms 304. The tightening of the nuts 318 will cause shoulders 324 on the blocks 302 to be clamped against the lower surface of the arms 304 at opposite sides of the slots 310.

15 The roll 92 is carried by the forked forward end of a cylindrical plunger 326 (Fig. 11) the rear portion of which is slidably mounted in a bearing 328 formed in the cutter head carrier 66. The stud 326 is connected with the cutter head 62 so that rearward displacement of the roll 92 caused by the pattern P will result in raising the cutters 18 into the plane of the work.

The cutter heads 62 and 64 are fast upon the 20 upper ends of two shafts 330 and 332 (Fig. 10) which are journaled in bearings in the carrier 66. The shaft 330 of the cutter head 62 is mounted to turn upon ball bearings 334 and 336 carried at the upper and lower ends respectively of a sleeve 338 which is mounted for axial sliding movement 25 within a bore 340 in the carrier 66 for the purpose of raising and lowering the beveling and roughing cutters 18. The shaft 332 of the cutter head 64 is mounted to turn on ball bearings 342 and 344 carried at the upper and lower ends respectively 30 of a sleeve 346 which is secured by means of a draw bolt 348 within a bore 350 in the carrier 66.

The 35 slide sleeve in which the shaft of the cutter head 62 is journaled is supported within the bore 340 in the carrier 66 by means of a yoke 356 formed in the forwardly extending arm of a bell crank lever 358 (Fig. 11), the yoke straddling the sleeve between the opposite sides of an annular groove 360 in the sleeve. The bell crank lever 358 is fulcrumed upon a stud 362 which is held 40 within a bore in the carrier 66 by means of a clamp bolt 364, the stud having a head 366 for holding the lever in position upon the stud. The bell crank lever 358 has an upwardly extending arm 368 the upper extremity of which extends 45 into a slot 370 formed in the rear portion of the cylindrical plunger 326 which is formed with a reduced forward portion which is slotted axially to receive the roll 92, and carries a pin 375 upon 50 which the roll 92 is mounted. A spring 380 engaging the rear of the arm 368 of the bell crank lever 358 tends to rock the lever in a direction to lower the cutter head 62 and normally holds the cutter head retracted in its lowermost position and yieldingly maintains the roll 92 in its normal 55 or forwardly displaced position. A stop screw 382 carried by the lever arm 368 is adapted to engage the finished surface on the carrier 66 and constitutes a setting-up adjustment to determine the 60 forwardly displaced position of the roll 92.

The cutter head shafts 330 and 332 extend 65 downwardly below their bearings within the carrier 66 and have belt pulleys 386 and 388 fixedly secured to their lower extremities. These pulleys are driven by means of a belt 390 which passes 70 over an idler pulley 392 mounted upon the cutter head carrier 66 and over a series of idler pulleys 394 which are carried by the arm 68 and over a large driving pulley 396 mounted to turn on the shaft 70 which carries the arm 68. Compounded 75

with the pulley 396 is a pulley 398. The second pulley 398 is driven by a belt 400 which passes downwardly over two idler pulleys 402 and over a driving pulley 404 (Fig. 3) which is fast to the front end of a horizontal shaft 406 that is journaled in bearings in the frame 50. The shaft 406 is driven by means of a belt 408 which passes over a pulley 410 that is fast on the rear end of the shaft 406 and over a driving pulley 412 on the shaft 414 of an electric motor 416 (Fig. 22). The motor 416 which is supported upon a bracket 418 bolted to the side of the frame 50 is also connected through the belt 408 with driving mechanism contained within the frame 50 which will be described in detail hereinafter and which operates through connections including the upright shaft 154 to drive the jack 54. The motor 416 is started and stopped through a switch and a push button 420 in a control box 422 secured to the head 52. While the motor 416 is running the cutter heads rotate continuously but the cycle of movements of the jack 54 is initiated by depression of the treadle 98 whereby starting and driving mechanism, which is contained within the frame 50 and which will be hereinafter described, is rendered operative to rotate the upright shaft 154. The jack is automatically stopped at the completion of its cycle of movements by stopping mechanism including the cam 156 carried by the guide block 142 on the jack carriage, which is adapted to engage a slide block 426 (Fig. 2) which is mounted upon the head 52 and which is operatively connected through a bell crank lever 428 and a link 430 with the driving mechanism above referred to. As shown, the bell crank lever 428 is fulcrumed upon a rod 432 carried by the head 52, the lever having a downwardly extending arm the lower end of which is received between two spaced lugs 434 on the slide block 426 and a rearwardly extending arm which is pivoted to the upper end of the link 430.

Each of the cutter heads 62 and 64 comprises a block or disk 440 (Figs. 10, 11 and 21) having a central aperture for receiving the upper end of the respective cutter head shaft 330 or 332. The shaft 330 extends upwardly through the cutter head 62 and through a central aperture in the rounding cutter 76 and is screw threaded to receive a nut 442 by means of which the cutter 76 is clamped to the cutter head and the cutter head is clamped to a flange 444 on the shaft. In a like manner, the shaft 332 extends upwardly through the cutter head 64 and through a central aperture in the edge trimming cutter 82 and is screw threaded to receive a nut 446 by means of which the cutter 82 is clamped to the cutter head 64 and the latter is clamped to a flange 448 on the shaft 332. A dowel pin 449 on each cutter head extends downwardly into a hole in the flange to which the cutter head is secured to prevent the cutter head from turning relatively to its shaft. As best shown in Figs. 12 and 21, the cutter head 62 has four beveling and roughing cutters 78. Each of these cutters consists of an elongated rectangular blade of substantial thickness. The cutter blades 78 are rigidly secured by means of bolts 450 to four upstanding marginal lugs 452 on the upper surface of the cutter head. The cutters 78 are clamped between the heads of the bolts 450 and the adjacent sides of the lugs 452 by means of nuts 454 on the bolts which are tightened against countersunk faces on the outer sides of the lugs. The lugs 452 are equally spaced from each other and from the center of the cutter head, and the surfaces on the lugs to which the cutters are se-

cured lie in planes which are parallel to but do not intersect the axis of the cutter head. As a result of this arrangement, the outer ends of the cutter blades have a substantial lead over their inner ends. Thus, the cutters will be enabled to cut more easily and less power will be required to rotate them than would be the case if their cutting edges extended radially of the cutter head. Extending diagonally across the upper edge faces of the cutter blades 78 are teeth 456 which are V-shaped in cross-section and which function to produce roughened surfaces on the work. The outer sides of the cutter blades are ground, as indicated at 458, to provide cutting edges at the outer or leading end of each tooth 456. The blades are made of substantial thickness, as already mentioned, to give them rigidity and to permit them to be repeatedly ground to sharpen the leading edges of the teeth. The lower longitudinal edges of the cutter blades bear against beveled surfaces 460 on the cutter head so that the cutter blades are held against turning about the clamp bolts 450 and are positioned with their toothed cutting edges inclined relatively to the plane of rotation of the cutter heads so as to bevel the margin of the sole. The upper edge of the blade is backed off at a substantial angle to provide clearance between the teeth and the work. The teeth 456 extend across the upper edge of the cutter at such angles that they are disposed lengthwise of the cuts or furrows which their cutting edges make in the sole and thus have no tendency to distort the furrows to any substantial extent.

The toothed cutting edge of each cutter will form a series of arcuate furrows in the margin of the sole each time the cutter is moved in an arcuate path across the sole. Inasmuch as the axis of the cutter head is perpendicular to the plane of the sole the cutters will generate a co-40 noidal surface as they rotate and consequently each tooth will cut deepest into the substance of the sole only while it is moving across a line which is both radial with respect to the cutter head and perpendicular with respect to the adjacent portion of the sole edge. After the cutting operation has started each cutter, in moving inwardly over the edge of the sole, will clear the substance of the sole and not cut into it until it approaches the perpendicular radial reference line above referred to, but as each cutter is moved past the above-mentioned reference line by the continued rotation of the cutter head, the cutter teeth will continue to cut for a substantial distance, the teeth cutting, however, less and less deeply into the sole substance as they advance and they may actually clear the surface of the sole before they pass outwardly over the sole edge. This is on account of the fact that, due to the advancing movement of the sole, the cutter as it sweeps inwardly encounters only that portion acted upon by the preceding cutter, whereas in sweeping outwardly it encounters material which has not previously been acted upon. The teeth of each cutter thus initially form a series of curved furrows which are substantially concentric (they would be actually concentric if the sole were not being moved past the cutter) and which extend from points near the above-mentioned reference line to points at, or spaced somewhat inwardly from, the edge of the sole. Substantially all of these furrows except only those portions which are located in the immediate vicinity of the reference line are cut away, however, by the action of the succeeding cutters. Consequently, during

the rotation of the cutter head, each tooth in the cutter blade which is at the instant acting upon the work leaves trailing behind it a single continuous furrow which is parallel to the sole edge and, since there is a row of regularly spaced teeth on each cutter blade, a corresponding series of regularly spaced grooves or furrows is formed in the sole margin, all the furrows being parallel to the sole edge. Each furrow thus ultimately formed in the sole is a curve which is tangent to the multiplicity of arcs initially produced each by a single operation of a cutter blade. In other words, each resulting furrow extends along a line which is one "envelope" of the series of circular arcs described by a single cutter tooth. The reducing and roughing cutters 80 which are carried by the cutter head 64 are similar to the cutters 78 just described and they are mounted in a similar manner upon the cutter head 64 except that the toothed cutting edges of the cutters 80 are inclined at a less angle to the plane of the sole than are the cutting edges of the cutters 78 so that the cutters 80 which operate around the forepart of the sole shall bevel the sole at a less steep angle than do the cutters 78 which operate along the shank portion of the sole. As already explained, the shank cutters 78 will not operate around the forepart of the sole because of the fact they are maintained in a lowered position while the forepart of the sole is moving past them. While the cutter head 64 has no up-and-down movement, it is obvious the cutters 80 on that head will not operate along the shank portion of the sole because the latter has already been beveled by the more steeply inclined cutters 78 when it reaches the field of action of the cutters 80.

The grooved or furrowed surface 248 produced by means of the cutters 78 and 80 is shown in perspective in Fig. 18 and in cross-section in Figs. 19 and 20. A surface of this character is ideal for the reception of cement inasmuch as the cement is permitted readily to penetrate deeply into the loosened fibers of the leather in such a manner as to insure a perfect bond between the cement and the leather. Inasmuch as the furrows extend lengthwise of the sole edge, they greatly facilitate a proper flowing or "leveling off" of the cement as the latter is applied. They also tend to prevent undesirable squeeze-out of the cement across the sole edge and upon the upper when the sole-attaching pressure is applied. Inasmuch as the cutters 78 and 80 are out of engagement with the material of the sole as the cutters move past the edge face of the sole, the cutters have no tendency to pull or direct the fibers of the leather outwardly over the sole edge. Consequently, the beveling or roughing operation does not result in the production of "fuzzy" edges such as are common to a sole the margin of which has been roughened by means of a cutter which cuts deeply into the substance of the sole while moving outwardly in directions substantially perpendicular to the sole edge.

The edge trimming cutter 82, which is also mounted upon the cutter head 64, is a single cutter having a plurality of peripheral teeth. This cutter is adapted to smooth and finish the edge of the sole and its teeth are shaped in cross-section, as best shown in Fig. 19, to impart to the sole edge a beaded finish such as that shown at 462 in Figs. 18 and 19. Preferably, the cutting edges of the teeth of the cutter 82 are slightly inclined in a direction to cause the finished sole edges to slope downwardly and inwardly from the flesh or at-

taching side of the sole in an amount sufficient to allow for the transverse curvature of a round bottom last so that, after the outsole has been attached to the shoe and curved to conform to the transverse curvature of the last bottom, the transverse elements of the trimmed and finished edge of the outsole will be "square", that is, they will extend vertically when the shoe occupies a normal upright position. It is usually desired to have the beaded edge finish only at the forepart of the sole. Accordingly, in order that the edge trimmer which operates around the forepart shall be rendered inoperative upon the shank portion of the sole edge, the roll 86 is made with the enlarged lower portion 90, already referred to. This enlarged portion 90 of the roll 86 is located in the plane of the grooved portions of the pattern and when it is received in the grooved portions of the pattern the cutter head carrier 66 will be so tilted that the edge trimming cutter 82 will operate upon the sole edge but, when the enlarged portion of the roll 86 is engaged by the ungrooved shank portion of the pattern, the carrier 66 will be tilted just sufficiently to remove the edge trimming cutter from operative engagement with the sole edge and consequently the latter will not operate along the shank portion of the sole edge. If it should be desired to trim and bead the shank portion of the sole edge, a guide roll 86 having no enlarged lower portion would be employed.

The driving mechanism, including the mechanism for starting and stopping the machine, will now be described. Referring first to Fig. 4, a driving shaft 470 is mounted for rotating and for endwise sliding movement. This driving shaft is rotated continuously from the belt 408 which, as has already been described, is driven from the motor 416 and operates also to rotate continuously the cutter heads 62 and 64. As shown in Figs. 4 and 22, the driving belt 408 passes over a pulley 464 that is mounted to turn on a stud 465 secured to a bracket 466 carried by the frame 50 and the pulley 464 is connected with the driving shaft 470 through reducing gearing comprising a pinion 467 compounded with the pulley 464 and a gear 468 fast on the driving shaft 470. To the right-hand end of this driving shaft 470 is fastened a friction clutch member 472 adapted to engage at times a friction clutch member 474 integral with a sleeve through which the shaft 470 extends, said sleeve being rotatably mounted in the frame 50 and having rigidly secured to it a bevel gear 476. The bevel gear 476 meshes with a bevel gear 478 fast to the lower end of the upright shaft 154 which, as already described, is connected to drive the jack carriage. The driving shaft 470 is moved first to the left and then to the right by a yoke 480 having its lower portion fastened to an outer end of a rockshaft 482. The upwardly extending arms of the yoke 480 are provided with rolls 484 which are located between two collars 486 that are fast to the driving shaft 470. The other end of the rockshaft 482 has fast to it the lower end of a shifting lever 488 (see also Fig. 5). In the operation of the machine, as will be described later, the shifting lever 488 is swung to the left, as viewed in Fig. 4, by means of a tension spring 490, to cause the bevel gear 476 to drive the upright shaft 154 to impart movement to the jack 54. The shifting lever 488 is then returned to the position shown, to stop the rotation of the shaft 154 so as to bring the jack to rest.

The movements of the shifting lever 488 are

controlled by a cam on a cam-shaft 492 which is caused to make half revolutions at proper times, the cam-shaft having fast to it a spiral gear 494 meshing with a small spiral gear 496 on an oblique shaft 498 which is journaled in bearings in the frame 50. A bevel gear 500 on the lower end of the oblique shaft 498 meshes with a bevel gear 502 on a horizontal countershaft 504 which is journaled in bearings in the frame 50 and is disposed 5 in coaxial relation to the driving shaft 470. The countershaft 504 has slidably keyed at its left-hand end a hub 506 which carries at its left-hand end a friction clutch member 508 and at its right-hand end a friction brake member 510. As shown, 10 the friction brake member 510 is being held against a stationary member 512 and the friction clutch member 508 is being held out of contact with the adjacent vertical face on the outer end of the friction clutch member 474 at the right-hand end of the driving shaft 470. The common 15 hub 506 of the friction members 508, 510 is engaged and moved first to the left and then to the right by two rolls 513 both of which are shown in Fig. 6 carried at the lower ends of the arms 20 of a short fork 514, the hub of which is rotatably mounted on a rod 516. Also integral with the hub 506 is an upwardly extending lever 518 which acts at proper times to shift the friction clutch member 508 and the friction brake member 510 to 25 impart half revolutions to the cam-shaft 492.

Before going further into the details of construction of the driving mechanism, the general mode of operation of the machine will be briefly described. With the parts of the machine in their 30 positions of rest, and while the clamp frame 96 is maintained in its lowered position by depression of the treadle 98, the operator places a sole in position against the bottom of the pattern P and then releases the treadle 98, allowing the 35 clamp member carried by the clamp frame 96 to clamp the sole to the pattern. The treadle 100 is then depressed to start the rotation of the countershaft 504 and the oblique shaft 498 to 40 impart a half revolution to the cam-shaft 492. During this half revolution of the cam-shaft 492, the driving shaft 470 is slid toward the left to 45 engage the clutch members 472 and 474 to start the rotation of the upright shaft 154 and finally the countershaft 504 and with it the oblique shaft 498 and cam-shaft 492 are brought to rest. 50 The jack 54 has now started its cycle of movements as a result of which the sole is carried past the cutters on the cutter heads 62 and 64. The movement of the jack continues until the cam 55 156 on the guide block 142 carried by the jack carriage 106 displaces the slide bar 426 (Fig. 2) thereby pulling up the link 430. Referring now to Fig. 4, the pulling up of the link 430 (the lower portion only of which is shown in this 60 figure) has the same effect as if the treadle 100 were again depressed. Consequently, a second half revolution is imparted to the cam-shaft 492. During this second half revolution of the cam-shaft 492 the jack is automatically stopped in 65 its initial position, as shown in Figs. 1 and 14, the driving shaft 470 is slid toward the right to return it to its normal position and the parts of the machine, with the exception of the cutter heads 62 and 64, the driving shaft 470, and the 70 operating connections between the driving shaft and the cutter heads, come to rest.

Referring now more particularly to Figs. 5, 6 and 7, the cam-shaft 492 and its associated parts will be described. On one side of the gear 494, 75 and rotatable with it and with the cam-shaft 492,

is a cam 520 having a cam track 522 in which runs a small roll 524 carried at the end of a control arm 526, the hub of which is rotatable on the rod 516. In the position of the parts shown, the shifting lever 518 is being held in a neutral position by a tension spring 528 fast at one end to the lever and at the other end to the frame 50, the spring holding an adjustable abutment 530 carried by the shifting lever against a stop 532 pivoted on the control arm 526 and held in the position shown by a small compression spring 534, a face on the lower portion of the hub of the stop 532 engaging at this time a shoulder on the control arm 526 which prevents further rotation of the stop clockwise, as viewed in Fig. 5. The abutment 530 is slidably mounted on the control lever 526 and may be adjusted by turning an adjusting screw 536. The stop 532 has a tail 538 and extending beneath this tail is the end of a lever 540 which may be swung upwardly about the axis 20 of a rockshaft 542 to which its hub is fast by pushing up a treadle rod 544, the upper end of which is pivoted to the lever 540. The treadle rod 544 has a vertical slot 546 in its lower end in which is received a pin 548 carried by an arm 25 550 fast on a rockshaft 552 to which the treadle 100 is secured. The treadle rod 544 has also a shoulder 554 against which there is held by a spring 556 a point of a small latch 558 which is pivoted to the treadle arm 550. A horizontal pin 30 560 carried by the frame 50 lies in the path of upward movement of a tail 562 of the latch 558. When the treadle 100 is depressed, the treadle rod 544 is pushed upwardly and then released. Upward movement of the treadle rod 544 causes the 35 right-hand end of the lever 540, as shown in Fig. 4, to swing up and engage the tail 538 of the stop 532 so as to disengage the stop from the abutment 530 on the shifting lever 518. The tension spring 528 then swings the lever 518 to the right, thereby 40 moving the brake member 510 and the friction clutch member 508 to the left. Engagement of the clutch member 508 with the clutch member 472 on the driving shaft 470 starts the rotation of the countershaft 504 and the cam-shaft 492. 45 During this half revolution of the cam-shaft 492, the control arm 526 moves first to the right and then to the left. In the left-hand movement of the control arm 526, the stop 532 returns the shifting lever 518 to the inoperative position 50 shown and stops the cam-shaft 492 at the end of the half revolution.

It has been explained that during this half revolution of the cam-shaft 492 the driving shaft 470 is slid to the left (Fig. 4) to cause the friction clutch member 472 to engage the friction clutch member 474 and thus to start the rotation of the upright shaft 154 to impart movement to the jack. It has also been explained that during the second half revolution of the cam-shaft 492 55 the driving shaft 470 is slid to the right so as to stop the rotation of the upright shaft 154 and thus to stop the movement of the jack. Referring now more particularly to Figs. 5, 6 and 7, the mechanism for thus sliding the driving shaft 60 470 will be described in detail. The starting of the rotation of the upright shaft 154 and the stopping of its rotation are brought about primarily by half revolutions of a cam 570 which is rigid with the worm gear 494 and the cam-shaft 492, the first half revolution of the cam being initiated by depression of the foot treadle 100 and the second half revolution of the cam being initiated by engagement of the cam 570 on the jack carriage with the slide block 426. In Fig. 5 65 70 75

the shifting lever 488 is shown in the same position in which it appears in Fig. 4, being so held by the tension spring 490 which exerts a continuous pull toward the right (viewing Fig. 5) 5 and holds a pin 572 carried by the shifting lever in engagement with one end of a slot 574 in a link 576 which is pivotally connected at its left-hand end with the upper end of an arm 578 the lower end of which is mounted to turn about 10 the rod 516. The arm 578 carries its upper end roll 580 which runs in a cam track 582 in the cam 570. During the first half revolution of the cam 570 the link 576 is moved to the right and brought to rest. During this movement of 15 the link 576 the tension of the spring 490 pulls the shifting lever 488 to the left (Fig. 4) thereby sliding the driving shaft 470 to the left, and starting the movement of the jack. The movement of the jack continues until the cam 156 on 20 the jack acts through mechanism which has been described to pull up the link 430 and then to release it. This movement of the link 430 produces the same effect, so far as the cam-shaft 25 492 is concerned, as would be produced by a second depression of the treadle 100, namely, it imparts a second half revolution to the cam-shaft. This second half revolution of the cam-shaft 492 pulls the link 576 back to the neutral position shown in Figs. 4 and 5, whereby the clutch 30 member 472 is disengaged from the clutch member 474, the upright shaft 154 ceases to rotate, and the jack comes to rest in its initial position.

Between successive operations of the machine the jack 54 remains at rest in the position indicated in Fig. 1, the longitudinal axis of the jack being substantially perpendicular to the guide rail 144 and the guide member 142 being in contact with the guide rail. In this position of the jack the toe end of the pattern P is directed toward the operator of the machine and the guide 35 rolls 84 and 86 on the cutter head carrier 66 are engaged by the cam 88 which functions at this time to hold the carrier supporting arm 68 retracted rearwardly against the force of the spring 262. The cutters on the carrier 66 are thus retracted from their normal work-engaging 40 positions to facilitate the introduction of a new piece of work into the machine. The driving shaft 470 and the cutter heads 62 and 64, however, rotate continuously, not only while a sole 45 is being operated upon but also during the intervals between operations while the jack is at rest.

It has already been explained that the clamp 50 frame 96 is lowered by depression of the treadle 98 to enable a sole to be placed upon the lower side of the pattern P in position to be operated upon, or to permit a sole which has been operated upon to be removed from the machine. 55 After a sole, such as the block sole S shown in Fig. 25, has been properly positioned beneath the pattern the treadle 98 is released, thereby causing the clamp frame 96 to be raised by means of the springs 202 and 204 so that the clamps 58 and 60 will clamp the sole firmly 60 against the lower side of the pattern, the clamp 65 60 yielding, if necessary, to equalize the clamping pressure exerted by the two clamps. The operator is now ready to initiate a cycle of operations 70 of the jack and he does this by depressing the treadle 100, after which the treadle is released to enable the automatic stopping mechanism to function to stop the jack at the end of the cycle. Depression of the treadle 100 results in connecting the cam-shaft 492 with the continuously ro-

tating driving shaft 470 so that a half revolution is imparted to the cam 570. At the start of this movement of the cam 570 the shifting lever 488 is swung to the left (as viewed in Fig. 4) to rotate the upright shaft 154 and operate the jack. The movement of the jack continues until it is automatically stopped at the end of a cycle of operations by a movement of the shifting lever 488 to the right, this movement resulting from the second half revolution of the cam 570.

The first movement of the jack is a rotary movement, the jack turning approximately 90° counterclockwise (viewed from above) about the center of curvature of the curved outer face of the guide member 142, thus moving the jack from the position indicated in Figs. 1, 14 and 23 to that indicated in Figs. 8 and 24. The position of the pattern P and the cam 88 relatively to the rolls 84, 86 and 92 and the cutters at this time is best shown in Fig. 24. It will be seen by reference to this figure that the rounding cutter 76 (not shown) has operated along the heel and shank portions at one side of the sole and that the beveling and roughing cutters 78 are operating upon the shank portion of the sole, the cutter head 62 which carries the cutters 78 being held in its raised or operative position by the cooperative engagement of the roll 92 with the ungrooved edge portion at the shank of the pattern. The cutter head 64 which carries the beveling and roughing cutters 80 and the edge trimming cutter 82 is still controlled by the cam 88, the cutters 80 and 82 not yet having started to operate upon the sole.

The Jack next slides toward the left until the inner curved face of the guide member 140 engages the sleeve 122. During this movement of the jack the edge of the pattern travels past the guide rolls 84 and 86 and the carrier 66 tilts about the axes of the trunnion 292 and the stud 296, the carrier supporting arm 68 swinging backwardly or forwardly about the post 70 as may be required to maintain engagement of the guide rolls with the pattern and thus to cause the actions of the various cutters to be controlled by the pattern. Figs. 25 and 26 show the position 45 of the pattern and sole relatively to the rolls 84, 86 and 92 and the cutters when the sliding movement of the jack has been approximately half completed. In the position of the parts shown the forepart beveling and roughing cutters 80 are 50 ineffective because they are located beneath the shank portion of the sole which has already been beveled and roughened by the cutters 78. The roll 92 has been received in the groove 172 in the forepart of the pattern and consequently the 55 cutter head 62 which carries the shank beveling and roughing cutters 78 has been lowered so that the cutters 78 are also ineffective. The rounding cutter 76, however, still remains operative, the action of this cutter being unaffected by the lowering of the cutter head 62 inasmuch as its cutting edges are long enough to extend completely across the sole edge when the cutter head 62 is in its lowered position as well as when it is in its upper position. The edge trimming cutter 82 is inoperative due to the fact that the relatively large lower portion 92 of the roll 86 is engaged by the ungrooved shank portion of the edge of the pattern so that the cutter head 64 has been displaced rearwardly just sufficiently to remove 70 the edge trimming cutter 82 from contact with the sole edge. Fig. 27 shows the position of the pattern and the sole relatively to the guide rolls and the cutters as the jack approaches the limit 75

of its above-mentioned sliding movement. As indicated by this figure, the rounding cutter 76 is still operating while the shank beveling and reducing cutters still remain inoperative because the cutter head 62 is still maintained in its lowered position. The forepart portion of the pattern and the sole having reached the field of action of the forepart beveling and reducing cutters 80, however, the latter cutters are operating to bevel 10 the forepart of the sole at an angle which is less steep than the angle of bevel in the shank. Moreover, the edge trimming cutter 82 is also operative because of the fact that the enlarged 15 lower portion 90 of the roll 86 has now been received within the groove 172 in the pattern and no longer functions to hold the edge trimming cutter rearwardly displaced in a position of clearance. The next movement of the jack is a rotation of 180° counterclockwise which causes the 20 cutters to operate around the toe of the sole. The jack then slides along the guide rail 144 toward the left until the inner curved face of the guide member 142 engages the sleeve 122, which movement carries that lateral edge of the sole 25 which has not yet been operated upon past the cutters, causing them to operate from toe to heel along that marginal portion of the sole which is opposite to that upon which they have already acted, thereby completing the operations upon 30 the sole. During this movement of the jack the cutters 78 are brought into action and the edge trimming cutter 82 is held out of action, in the shank portion of the sole, by the rearward displacement of the roll 92 upon engagement of the 35 ungrooved shank portion of the pattern edge therewith, as at the opposite side of the sole. During this movement of the jack also the cam 88 operates to initiate the second half revolution of the cam 570 which finally stops the movement of the jack. Before the jack stops, however, it 40 turns 90° about the center of curvature of the guide member 142 whereby it is returned to its initial position of rest and the pattern and sole are positioned to facilitate removal of the sole.

Having described my invention, what I claim 45 as new and desire to secure by Letters Patent of the United States is:

1. In a machine for operating upon soles, a tool for simultaneously beveling and furrowing the surface of the marginal portion of a sole, and 50 means for effecting relative movement of said tool and a sole in a manner to cause a combined beveling and marginal surface furrowing operation to progress lengthwise of the sole margin.
2. In a machine for operating upon soles, 55 means for supporting a sole, means for beveling the sole edge at one angle in one portion of the sole and at another angle in another portion of the sole, said means being adapted to roughen the portion of the sole operated upon, and means 60 for effecting relative movement of said beveling means and a sole to cause said means simultaneously to bevel and roughen the sole.
3. In a machine for operating upon soles, a tool for beveling the marginal portion of a sole at a 65 relatively large angle, a second tool for beveling another marginal portion of the sole at a relatively small angle, means for relatively moving said tools and a sole to cause the tools to bevel the sole, and means for moving the first tool 70 relatively to the second tool to prevent the first tool from operating along a predetermined portion of the margin of the sole.
4. In a machine for operating upon soles, two beveling tools arranged to operate successively 75

upon a sole, one of said tools being constructed and arranged to bevel the sole edge at a relatively abrupt angle to the surface of the sole and the other of said tools being constructed and arranged to bevel the sole edge at a relatively slight angle to the surface of the sole, means for supporting the sole and moving it to advance its marginal portion progressively past said tools, a sole pattern for controlling the action of said tools, and mechanism including means on said pattern for retracting one of said tools from operative position during the movement of the sole past said tools. 5

5. In a machine for operating upon soles, a support for a sole, and means for performing a combined rounding, edge reducing and surface furrowing operation upon the marginal portion of a sole on said support. 10

6. In a machine for operating upon soles, a cutter head having cutters thereon for performing rounding, edge reducing and surface furrowing operations upon a sole, and means for relatively moving said cutter head and a sole to cause said cutters to round the sole and to perform a combined edge reducing and surface furrowing operation thereon. 20

7. In a machine for operating upon soles, a cutter head having cutters for performing a rounding and roughing operation upon a sole, a second cutter head having cutters for performing a finishing operation upon the rounded edge 25 of the sole, and means for relatively moving said cutter heads and a sole to cause said cutters to operate successively upon the sole. 30

8. In a machine for operating upon soles, a support for a sole, a cutter for performing an initial rounding operation upon the sole, means for performing a combined reducing and roughing operation upon a marginal portion of the sole, a cutter for performing a final edge trimming operation upon the sole, and means for relatively moving said cutters and the sole support to cause the cutters to operate successively on a sole thereon. 35

9. In a machine for operating upon soles, a tool for rounding a sole and beveling a marginal portion thereof, a second tool for trimming the rounded edge of the sole and beveling another marginal portion of the sole at an angle different from that produced by the first tool, and means for relatively moving said tools and the sole to cause said tools to operate successively upon the sole. 45

10. In a machine for operating upon soles, tool-carrying means, sole-supporting means, means for relatively moving and guiding said tool-carrying means and said sole-supporting means to traverse one past the other, and tools on said tool-carrying means for performing at one such traverse two different operations on a face of the sole and two different operations on the sole edge. 55

11. In a machine for operating upon soles, tool-carrying means, a sole support, means for relatively moving and guiding said tool-carrying means and said sole support to traverse one past the other, and tools on said tool-carrying means operative at one such traverse to round a sole on said support, to bevel the sole edge, and to roughen a marginal portion at one side of the sole to prepare the sole for the reception of sole-attaching cement. 65

12. In a machine for operating upon soles, tool-carrying means, a sole support, means for relatively moving and guiding said tool-carry- 70

- ing means and said sole support to traverse one past the other, and tools on said tool-carrying means operative at one such traverse to perform an initial rounding operation upon a sole on said support, to roughen a marginal portion at one side of the sole, and to perform a final finishing operation upon the rounded sole edge.
13. In a machine for operating upon soles, tool-carrying means, a sole support, means for relatively moving and guiding said tool-carrying means and said sole support to traverse one past the other, and tools on said tool-carrying means operative at one such traverse to round a sole on said support, to reduce and roughen a marginal portion at one side of the sole, and to trim a portion only of the rounded edge of the sole.
14. In a machine for operating upon soles, a tool carrier, a sole support, means for relatively moving and guiding said tool carrier and said sole support to traverse one past the other, and tools on said tool carrier operative at one such traverse to round a sole on said support, to bevel the edge of the shank portion of the sole, and to trim the beveled edge portion of the sole.
15. In a machine for operating upon soles, a tool carrier, a sole support, means for relatively moving and guiding said tool carrier and said sole support to traverse one past the other, and tools on said tool carrier operative at one such traverse to round a sole on said support and to form a beaded finish upon the rounded sole edge.
16. In a machine for operating upon soles, tool-carrying means, a sole support, means for relatively moving and guiding said tool-carrying means and said sole support to traverse one past the other, and tools on said tool-carrying means operative at one such traverse to round a sole on said support and to bevel the marginal portion of the sole at one angle in the shank and at a different angle about the forepart.
17. In a machine for operating upon soles, a tool carrier, a sole support, means for relatively moving and guiding said tool carrier and said sole support to traverse one past the other, tools on said tool carrier operative during one such traverse to round a sole on said support and to perform a combined reducing and roughing operation upon the shank portion of the sole, and other tools on said carrier operative during said traverse to roughen the marginal portion of the forepart of the sole and to impart a smooth finish to the rounded sole edge.
18. In a machine for operating upon soles, tool-carrying means, a sole support, means for relatively moving and guiding said tool-carrying means and said sole support to traverse one past the other, a tool on said tool-carrying means for performing an initial rounding operation upon a sole on said support, a second tool on said tool-carrying means for beveling a marginal portion of the sole, both of said tools operating during one such traverse of said tool-carrying means and said sole support, and means for moving said tool-carrying means to retract said second tool from work-engaging position, said first tool being constructed and arranged to remain operative when said second tool has been retracted.
19. In a machine for operating upon soles, a rotary roughing tool, means for supporting a sole in a plane at right angles to the axis of said tool, and means for relatively moving said tool and said sole supporting means as the tool rotates to cause the tool to operate progressively along the marginal portion of the sole, said tool having a work-en-
- gaging portion constructed and arranged to produce in the marginal portion of the sole a series of furrows extending in directions parallel to the edge of the sole.
20. In a machine for operating upon soles, a rotary roughing tool, means for rotating the tool, means for supporting a sole in a plane at right angles to the axis of said tool, and means for relatively moving said tool and said sole supporting means as the tool rotates to cause the tool to operate progressively along the marginal portion of the sole, said tool being constructed and arranged to produce a series of furrows in the surface of the sole as the tool rotates, and said tool having its work-engaging portion inclined relatively to the axis of rotation of the tool to cause said furrows to be disposed in parallel relation to the edge of the sole.
21. In a machine for operating upon soles, a rotary roughing tool, means for rotating the tool, means for supporting a sole in a plane at right angles to the axis of said tool, and means for relatively moving said tool and said sole supporting means as the tool rotates to cause the tool to operate progressively along the marginal portion of the sole, said tool having a cutting edge constructed and arranged to produce a series of furrows in the surface of the sole as the tool rotates, said edge being inclined to cause its outer portion to cut in advance of its inner portion thereby to improve its cutting action.
22. In a machine for operating upon soles, a rotary cutter having a toothed cutting edge arranged to generate a toothed conoidal surface of revolution, and means for supporting a sole in a plane at right angles to the axis of said cutter and for moving the sole to advance the marginal portion of one of its faces progressively past said cutter thereby causing the latter to cut furrows in said marginal portion which are parallel to the edge of the sole.
23. In a machine for operating upon soles, a rotary cutter having a toothed cutting edge, means for rotating the cutter, means for supporting a sole in a plane at right angles to the axis of rotation of the cutter, means for relatively moving the cutter and the sole support to cause the cutter to operate progressively along a marginal portion of a sole, the toothed cutting edge of the cutter being inclined relatively to the surface of the sole to cause the cutter teeth to cut furrows in the sole extending along lines which are envelopes of the arcs of travel of the cutter teeth.
24. In a machine for operating upon soles, spaced rotary beveling cutters having parallel axes and toothed cutting edges, means for rotating the cutters, means for supporting a sole in a plane at right angles to the axes of rotation of said cutters, means for relatively moving the cutters and the sole support to cause the cutters to operate progressively along a marginal portion of one face of a sole on said support, the leading cutter being shaped to bevel the sole at a greater angle than the other cutter, and means for retracting said leading cutter from operative engagement with the sole after it has operated along a predetermined portion of the sole margin to enable the other cutter to operate to bevel the sole at a less angle than the first cutter.
25. In a machine for operating upon soles, two rotary cutters, means for rotating said cutters, a sole-shaped pattern, a clamp for holding a sole on the pattern, means for moving the pattern to traverse the marginal portion of the sole past said

- cutters to cause said cutters to operate upon the marginal portion of the sole during said traversing movement, a carrier for said cutters, a support on which said carrier is mounted for tilting movement, rolls coaxial with said cutters for cooperating with the pattern to control the tilting movement of said carrier, and means for pressing said support toward the pattern to maintain said rolls in engagement with the pattern.
26. In a machine for operating upon soles, two rotary cutter heads, means for rotating the cutter heads, a sole-shaped pattern having a groove in a portion of its edge face, a clamp for holding a sole on the pattern, means for moving the pattern to traverse the marginal portion of the sole past said cutter heads, cutters on said cutter heads for operating upon the marginal portion of the sole during said traversing movement, a carrier for said cutter heads, a support on which said carrier is mounted for tilting movement, rolls on said carrier for cooperating with the pattern to control the tilting movement of said carrier, means for retracting one of said cutter heads from operative position, a roll on said carrier for cooperating with said groove to control the retraction of said cutter head, and means for pressing said support toward the pattern to maintain said rolls in engagement with the pattern.
27. In a machine for operating upon soles, a pattern having means for clamping a sole thereon, a carrier movable in directions toward and from the pattern, a tool on said carrier for operating upon the marginal portion of the sole, a roll on said carrier for cooperating with the pattern to control the action of said tool, a jack movable to traverse the marginal portions of the pattern and the sole past said roll and said tool respectively, operator-controlled means for initiating the movement of the jack, and automatic means for stopping the jack at the completion of one such traversing movement of the pattern and sole.
28. In a machine for operating upon soles, a sole-shaped pattern having a groove in its edge face extending lengthwise thereof, a clamp for holding a sole on one side of the pattern, a tool for operating upon the marginal portion of the sole, a guide roll having a portion for cooperating with the edge of the pattern at one side of said groove to guide the tool while operating upon one portion of the sole margin and having another portion located in line with said groove and adapted to be received in the latter and to cooperate with an ungrooved portion of the edge of the pattern in line with said groove for controlling the operation of said tool upon another portion of the sole margin, and means for imparting a relative movement of translation to the sole and said tool for causing said tool to operate along such line of movement.
29. In a machine for operating upon soles, a sole-shaped pattern having a groove in its edge face extending lengthwise thereof, a clamp for holding a sole on one side of the pattern, a tool guided by the ungrooved edge portion of the pattern for rounding the sole, a second tool guided by the grooved portion of the pattern for operating upon the exposed face of the sole, means for supporting the pattern and said tools and for imparting a movement of translation to the sole and said tools to cause said tools to operate along such line of movement, and means controlled by said grooved portion of the pattern for relatively moving said pattern and said tools to control the operation of said second tool, said first tool being constructed and arranged to operate to remain operative regardless of the relative positions of the tools and the pattern.
30. In a machine for operating upon soles, a cutter head carrier, a sole supporting pattern, means for clamping a sole on said pattern, two rotary cutter heads on said carrier, means for rotating said cutter heads, tools on each cutter head for performing different operations upon the edge of a sole on said pattern, tools on said cutter heads for performing different operations upon one face of the sole, means for moving the pattern to traverse the marginal portion of the sole past said tools, means associated with said cutter heads and arranged to cooperate with said pattern for guiding said cutter heads during said movement of said pattern, said guiding means and said pattern being constructed and relatively arranged to displace one cutter head in a direction transverse to its axis of rotation to render inoperative one of the tools for operating upon the edge of the sole, and means for displacing the other cutter head in an axial direction to render inoperative one of the tools for operating upon a face of the sole.
31. In a machine for operating upon soles, a tool head carrier, a sole-shaped pattern having a groove in its edge face extending about the forepart of the pattern and having ungrooved portions in line with said groove in the shank of the pattern, means for clamping a sole upon the pattern, two rotary tool heads on said carrier, a reducing and roughing tool on each tool head for operating upon one face of the sole, means for moving the pattern to traverse the marginal portion of the sole past said tools, and means for moving one of said tool heads relatively to said carrier to render the reducing and roughing tool carried thereby operative upon the shank portion of the sole and inoperative upon the forepart of the sole, said means including a roll on said carrier for cooperating with said groove and with said ungrooved portions of the pattern.
32. In a machine for operating upon soles, a tool head carrier, a sole-shaped pattern having a groove in its edge face extending about the forepart of the pattern and having ungrooved portions in line with said groove in its opposite lateral edge faces, means for clamping a sole against one side of the pattern, two rotary tool heads on said carrier, a tool on each tool carrier for performing an edge trimming operation upon the sole, means for moving the pattern to traverse the marginal portion of the sole past said tools, two rolls associated one with each of said carriers for cooperating with the edge of the pattern along a portion out of line with said groove for controlling the operation of said tools, and means on one of said rolls arranged to enter said groove and to cooperate with said ungrooved shank portions of the edge of the pattern to render one of said tools ineffective to operate about the forepart of the sole.
33. In a machine for operating upon soles, a jack mounted for movement in a plane inclined to the horizontal to carry the marginal portion of a sole supported by the jack past an operating point, means on the jack for supporting a sole pattern, and a clamp on the jack for clamping a sole against the pattern, said clamp having a work-engaging surface elongated lengthwise of the pattern and being adjustable about an axis perpendicular to said surface to accommodate different soles.
34. In a machine for operating upon soles, a

5 jack having means for supporting a sole pattern, the jack being movable to carry the marginal portion of a sole on the pattern past an operating point, a clamp frame on the jack, a clamp on said frame for holding the forepart of the sole against the pattern, and a second clamp on said frame for holding the heel portion of the sole against the pattern, said clamps being relatively adjustable lengthwise of the sole and angularly in a plane 10 parallel to the face of the sole to accommodate soles of different sizes and styles.

15 35. In a machine for operating upon soles, a jack carriage mounted for sliding and turning movement, means on the jack carriage for supporting a sole pattern, a clamp frame carried by the jack carriage, spring means for urging the clamp frame toward operative position, a heel clamp on said frame for engaging the heel portion of a sole to clamp it against the pattern, and 20 a forepart clamp on said frame for clamping the forepart of the sole against the pattern, one of said clamps being yieldable relatively to the jack frame to equalize the clamping pressure exerted by said clamps.

25 36. In a machine for operating upon soles, a post, a jack mounted for sliding and rotative movement with respect to said post, means on the jack for supporting a sole pattern, a movable clamping member for holding a sole against the pattern, and means extending through said post for releasing said movable clamping member.

30 37. In a machine for operating upon soles, a jack, means on the jack for supporting a pattern and for clamping a sole on the pattern, a movable carrier, means tending to move the carrier toward the pattern, a cutter on said carrier rotatable about an axis perpendicular to the plane of the sole for reducing a marginal portion of the sole, said cutter being movable also in an axial 40 direction, means for moving the jack to advance the marginal portion of the sole past said cutter, a roll associated with said cutter for cooperating with the pattern to control the movement of said carrier, mechanism for moving said cutter axially 45 to remove it from operative position, and means on the pattern for controlling the movement of said mechanism.

35 38. In a machine for operating upon soles, a sole-shaped pattern having a groove in its edge face extending about the forepart of the pattern and having an ungrooved edge portion in line with said groove in its shank portion, means for clamping a sole against one side of the pattern, a carrier movable toward and from said pattern, two tool heads mounted on said carrier with their axes perpendicular to the sides of the pattern, one of said heads being movable in an axial direction, reducing and roughing tools on each tool head for operating upon one face of the sole, means 50 for moving the pattern to traverse the marginal portion of the sole past said tools, a roll on said carrier for cooperating with a portion of the pattern edge out of line with said groove to control the relative movements of said tools and the sole in directions parallel to the plane of the sole, means for imparting axial movement to one of said tool heads, and means on said carrier adapted to be received in said groove and to cooperate with said ungrooved shank portion of the pattern to control the axial movements of said tool head to cause the tools carried thereby to operate only upon the shank portion of the sole.

40 39. In a machine for operating upon soles, a

sole-shaped pattern having a groove in its edge face extending about the forepart of the pattern and a groove in its edge face at the heel portion of the pattern and having an intermediate ungrooved edge portion in line with said grooves in its shank portion, means for clamping a sole against one side of the pattern, a carrier movable toward and from said pattern, two tool heads mounted on said carrier with their axes perpendicular to the sides of the pattern, one of said tool heads being movable axially in said carrier, reducing and roughing tools on each tool head for operating upon one face of the sole, an edge trimming tool on each tool head, means for moving the pattern to traverse the marginal portion of the sole past said tools, means on said carrier for cooperating with the edge of the pattern at one side of said grooves to control the relative movements of said tools and the sole in directions parallel to the plane of the sole, means for moving one of said tool heads axially, and means on said carrier adapted to be received in said grooves and to be displaced by said ungrooved shank portion of the pattern to control the axial movements of said tool head to cause the beveling and roughing tools carried thereby to operate only upon the shank portion of the sole.

45 40. In a machine for operating upon soles, a pattern having a sole clamped thereon, a carrier movable in directions toward and from said pattern, a rotary cutter head on said carrier, a cutter on said cutter head arranged to reduce and roughen the marginal portion of the sole, a second cutter on said cutter head for trimming the sole as its marginal portion is being reduced and 50 roughened, a roll on said cutter head carrier for cooperating with said pattern to control the action of said cutters, and means for moving said pattern to traverse the marginal portions of the pattern and the sole past said roll and said cutters respectively.

45 41. In a machine for operating upon soles, a sole-shaped pattern, means for clamping a sole upon the pattern constructed and arranged to leave the marginal portion at one side of the sole 55 unobstructed, a carrier mounted to turn about an axis perpendicular to the face of the pattern, a rotary edge finishing cutter head rotatable about an axis parallel to the axis of said carrier, an edge finishing cutter and also a beveling and roughing cutter on said cutter head, a rounding cutter head on said carrier rotatable about an axis parallel to the axis of said carrier, said cutter head being movable axially relatively to said carrier and pattern, a rounding cutter and also a beveling and 60 roughing cutter on said rounding cutter head constructed and arranged to bevel the sole at a steeper angle than said first beveling cutter, two rolls on said carrier coaxial with said cutter heads for cooperating with the edge of said pattern to control the positions of the cutter heads relatively to the sole, means for moving said pattern to traverse the margin of the pattern and the sole past said rolls and said cutters, respectively, and mechanism including means on said pattern and cooperating means on said carrier for moving said rounding cutter head axially during said traversing movement.

45 42. In a machine for operating upon soles, a sole-shaped pattern having a groove in the edge of its forepart and an ungrooved edge in its shank portion, means for clamping a sole against one side of the pattern, a carrier movable in directions toward and from the pattern, a rotary cutter head on said pattern, a reducing and roughing

cutter and an edge trimming cutter on said cutter head, a roll on said carrier having a portion of relatively small diameter for cooperating with the edge of the pattern in a plane out of line with 5 said groove for controlling the action of the reducing and roughing cutter and having a portion of relatively large diameter adapted to be received in said groove and to cooperate with the ungrooved edge in the shank portion of the pat-

tern, means for moving said pattern to traverse the marginal portions of the pattern and the sole past said roll and said cutters, respectively, and means controlled by the relatively large portion of said roll for retracting the edge trimming cutter from operative engagement with the sole while the shank portion of the sole is being moved past the cutters. 5

ERNEST W. STACEY.
